UNITED STATES PATENT OFFICE.

RICHARD ALBERT FEISS, OF CLEVELAND, OHIO.

PRICE-SLIP FOR PIECEWORK.

1,272,243.

Specification of Letters Patent.

Patented July 9, 1918.

Application filed October 4, 1916. Serial No. 123,756.

To all whom it may concern:

Be it known that I, RICHARD A. FEISS, a citizen of the United States, residing at Cleveland, in the county of Cuyahoga and State of Ohio, have invented a new and useful Price-Slip for Piecework, of which the following is a specification.

This invention has reference to price slips for piece-work, and its object is to provide a tabulated form whereby the total amount of several batches of piece-work is ascertained without the necessity of addition of numerous small sums.

In shops where piece-work is performed, the work is often given out in lots or batches, each batch being finished before the next is given out. Certain classes of work have a prevailing price for each piece and other classes of work have other prices. It is customary, however, for a piece-worker to be employed upon the same character of work and hence a single slip will answer for a day's work.

Experience has demonstrated that a single worker may do a certain number of pieces per day and hence the price-slip is divided into a sufficient number of spaces or boxes to cover the number of pieces which may be finished in a day or other chosen time period.

The sections or boxes contain a series of numbers progressively increasing by units, and associated with such numbers are other numbers correspondingly increasing in value by amounts represented by the basic price per piece. Each section or box, therefore, contains a number representing a number of pieces and another number representing a sum equal to the number of pieces times the basic price per piece.

The different slips may have different basic values per piece, with the value numbers differing correspondingly, while the numbers representing the pieces of work performed may be the same. Each slip contains spaces for data and may have certain imprints.

The invention will be best understood from a consideration of the following detailed description, taken in connection with the accompanying drawing forming part of

this specification, with the further understanding that while the drawing shows a practical form of the invention, the latter is not confined to strict conformity with the showing of the drawing, but may be changed and modified, so long as such changes and modifications come within the scope of the appended claim.

In the drawing, the figure is a representation of a piece-slip filled out to represent a day's work.

Referring to the drawing, there is shown a sheet 1, usually of paper, which sheet may be and usually is somewhat smaller than the drawing shows, but the size of the slip is of no particular moment, except that it is advisable to have it large enough to be clearly legible.

By means of longitudinal lines 2, 3 and other lines 4, 5, perpendicular to the first named lines, the main portion of the sheet is divided into many rectangular boxes or spaces 6, in which are consecutively arranged numbers 7, progressively increasing by units, and made sufficiently prominent to be readily read.

The topmost longitudinal line 2 may be somewhat heavier or more pronounced in appearance than the other longitudinal lines and is spaced a sufficient distance from what in use constitutes the top edge of the sheet to provide room for imprints and applied data. The imprints are arranged within a space 8, near one end of the sheet above the line 2 and may include the words "Slips", "Hours", "In", "Out", and "Price", with blank spaces associated with the words, which spaces are filled in as desired with suitable data. The rest of the space above the line 2 is divided into other spaces 9, 10 respectively, the space 9 being reserved for a date and the space 10 for the employee's name and description of the character of the work performed, and such other data as may be desired.

The particular arrangement with respect to the spaces at the top of the sheet for data is not at all obligatory since other arrangements may be adopted.

The number of rectangular spaces or boxes

6 into which the main body of the sheet is divided is not necessarily a fixed number. In the particular sheet shown, the number of spaces or boxes reach 500 and these boxes 5 are numbered consecutively from 1 to 500, the numbers running lengthwise of the sheet in order with heavy upright lines 4 dividing the longitudinal lines of numbers into groups of ten, this arrangement being one 10 of convenience. For different classes of work, different prices per piece are paid. It may be assumed that the price per piece for which the slip shown in the drawing is designed is $5\frac{1}{2}$ mills, and is represented on the 15 slip after the word "Price" as .0055. Consequently in the box containing the number 1, there is also contained the number .0055, in box 2 is the number 011, in box 3 is the number .0165, and so on throughout the numbers 20 up to 500, where the price number is 2.75, this last number representing 500 times .0055. The consecutive numbers, therefore, represent pieces of work to be performed, while the other numbers accompanying them represent the amount earned for 25 the number of pieces of work at the basic price appearing at the top of the slip. Since all of these numbers are printed, slips must be prepared for each basic price per piece.

30 When an employee reports for work, he is given a slip which in turn is given a slip number. In the drawing the slip number is 1 and is placed after the word "slips" by a suitable writing implement such as a pen 35 or pencil. The time the employee goes to work is entered on the slip after the word "In", and in the particular showing of the drawing, this is indicated by "7.00", meaning seven o'clock. The time the employee 40 quits work is placed after the word "Out", and in the particular showing of the drawing this is given as "4.30". The number of hours the employee actually works is placed after the word "hours" and in the particular 45 slip represented in the drawing, this is given as 9.

In the space 9 is entered the date on which the work is performed, while in the space 10, there is entered the name of the 50 workman and the character of the work performed which latter it is customary to put down in abbreviated form. Now with such a piece-work price slip properly filled out to identify the workman at the beginning of the day, let it be assumed that the 55 workman is given a batch of work with the arbitrary number 23, and contains 11 pieces or articles. A line represented at 12 is drawn around the number 11 of the series 60 of numbers on the sheet, the box containing the number 11 also containing the number 0605, which represents the amount to be paid for 11 pieces of work at 0055 per piece.

At some point preceding the number 11, the number 23 is written, such writing being 65 represented at 13. The workman, having finished batch number 23, is given batch number 24, which batch contains 6 articles. The number of articles added to those in the first batch total 17, so a line 14 is drawn 70 about the block containing the number 17 and the number 24 represented at 15 is placed at a point preceding the number 17.

Let it be assumed that batch 25 contains 75 18 pieces, so that the next number to be encircled by a line is 35. Let it further be assumed that the next batch is batch 26 and contains 35 pieces, whereupon the block containing the number 70 is inclosed in a line. In this way various numbers are 80 designated on the sheet by inclosing lines and in the particular example shown in the drawings, the last batch is numbered 31, as indicated at 16, while the total number of pieces in all the batches amounts to 435, 85 which number is inclosed by the line 17 and represents the total earnings for the work done as 2.3925. In this way the amount of the work performed is very readily taken care of and the amount earned is ascertained from the box containing the highest 90 number representing the number of pieces of work done during the time period. Such slips may be filled out from day to day and at the end of a stated period, say a week, 95 it is a simple matter to ascertain and add up the daily earnings, instead of having to keep track of a large number of small sums, with many multiplications and additions and a constant liability of mistake. 100

The piece work time slips reduce the chance of error to an extreme minimum, tedious and time consuming calculations being entirely eliminated to the benefit of both the employer and the employee. 105

What is claimed is:—

A price slip for piece work employees covering a definite period of time, comprising a paper sheet divided by lines into a consecutive series of inclosed spaces or 110 boxes, and headed by a number representing a basic price per piece for work, and designated spaces in which to fill out the time covered by the slip, each box containing two superposed numbers, one number representing the serial number of the box and 115 designating the number of pieces in each batch or lot of work which may be given to the employee during said period of time, which boxes are numbered consecutively throughout the sheet, the other number representing the product of the basic rate displayed on the sheet head multiplied by the serial number of the box and designating the amount earned at the basic 120 rate for the number of pieces completed, 125

whereby the pieces of work and the amounts earned therefor may be designated by lines drawn about individual boxes, the last box marked on the sheet indicating the amount 5 earned by the employee and the number of pieces of work completed for the period covered by the slip.

In testimony, that I claim the foregoing as my own, I have hereto affixed my signature in the presence of two witnesses.

RICHARD ALBERT FEISS.
